UNITED STATES PATENT OFFICE.

WILLIAM H. PAYNE, OF GRINNELL, IOWA, ASSIGNOR OF THREE-FOURTHS
TO JAMES K. WORTHINGTON, OF KIRKWOOD, AND CHARLES D. MOODY,
OF WEBSTER GROVES, MISSOURI.

HARVESTER.

SPECIFICATION forming part of Letters Patent No. 392,687, dated November 13, 1888.

Application filed May 19, 1883. Serial No. 95,456. (No model.)

To all whom it may concern:

Be it known that I, WILLIAM H. PAYNE, of Grinnell, Iowa, have made a new and useful Improvement in Harvesters, of which the following is a full, clear, and exact description, reference being had to the annexed drawings, making part of this specification, in which—

Figure 1 is a view in perspective of a harvester having the improvements. Such features of a harvester as are unessential to an understanding of the improvement are not exhibited. Fig. 2 is a vertical transverse section of the harvester; and Figs. 3, 4, 5, 6, 7, and 8 are details, Fig. 3 being an elevation of the mechanism for delivering the bundles from the region of the binder into the bundle-carrier, Figs. 4 and 5 sections on the line 4 5 of Fig. 3, Figs. 6 and 7 side elevations showing the means for rotating the fork of the transfer device, and Fig. 8 an end view of the separator device.

The same letters of reference denote the same parts.

The present invention is an improvement in harvesters having self-binder attachments and bundle-carriers; and it consists in the matter substantially as is hereinafter set forth and claimed, aided by the annexed drawings.

In the drawings, A represents a harvester having a self-binder attachment. Many of the familiar details of a harvester and binder attachment are not shown, as they are not essential to an understanding of the improvement, which relates more especially to the bundle-carrier and the parts therewith operating.

B represents the bundle-carrier, which is constructed and arranged to receive the bundles as they come from the self-binder, and is adapted to discharge them at the will of the operator in charge of the carrier. The carrier, so far as supporting the bundles is concerned, may be variously shaped and constructed, and to discharge the bundles the carrier may be turned, tilted, or opened; but, whatever means are employed to discharge the bundles from the carrier, they should be independent of the mechanism of the binder and under control of the operator, so that, although the bundles may be mechanically and regularly delivered from the binder, they can be dropped from the carrier at the will of the operator and at regu-

lar or irregular intervals of time or space, as desired.

The binder may be located at any suitable part of the harvester; but wherever it is placed, whether on the inner or the outer side of the master-wheel, the cut grain, by means of suitable and well-known mechanism, is delivered into its vicinity and to the gavel-forming mechanism, and the bundles, after leaving the bundle-ejector, fall (when bound by the binder mechanism) onto or into the carrier. In the present instance the binder is located at C upon the inner side of the master-wheel D, between the wheel and the platform E, and the bundles as they come from the binder are transferred upward and over into the carrier B. The details of the binder, as stated, are not shown.

The cut grain is transferred over the platform E by a suitable rake, F. A separator, G, transfers the grain from the rake and delivers it in gavels to the binder, and the bundles, when bound by the binder and delivered therefrom, are transferred by the bundle-discharge H upward along the way I to the top of the master-wheel casing J, whence they fall into the carrier, the movement of the grain and bundles being indicated by the various arrows in Fig. 2.

The carrier B is made to hold the bundles as they fall, and, in place of being simply a flat surface, it preferably is shaped to arrest and catch the bundles as they are tossed into it, and it has sufficient depth to hold the desired number of bundles. To this end the carrier B has two sides, b and b', the side b being for sustaining the carrier-load on the side toward the binder, and the side b' being for sustaining the carrier-load on the opposite side. The sides b b', for this purpose, may be of any suitable construction. The side b is suitably supported upon the harvester-frame, and is preferably the outer portion of the master-wheel casing—that is, it keeps the bundles from the wheel. The opposite side, b', is supported by the arms K K, which project from the main portion of the harvester-frame. To discharge the bundles the carrier is made to open at the bottom and allow the bundles to drop to the ground. To this end

the preferable practice is to have the side b' to open away from the side b , and for this purpose the side b' is journaled at $b^2 b^2$ in the arms K K. The side b' can then be swung apart 5 from the side b , substantially as indicated by the broken lines B', Fig. 2, and when the sides are thus separated at their lower ends the bundles drop from the carrier. The sides $b b'$ should be constructed to enable the bundle to 10 readily drop to the ground when the carrier is opened.

It is important to be able to discharge the bundles from the carrier at certain points in the field being harvested, and to this end the 15 opening of the carrier is made to be controlled by an attendant, who may be the driver of the machine or an attendant especially in charge of the carrier. The means selected for moving the side b' is a lever, b^3 , which is attached 20 to the side b' in the region of the journal b^4 , and adapted to be operated by an attendant, who may occupy the seat L, and by moving the lever can swing the side b' upon its bearings $b^2 b^2$. A spring-dog, b^5 , may be used to 25 hold the side b' closed; or the attendant, by retaining his hold upon the lever, may control the position of the side b' .

The relative position of the binder mechanism and the bundle-carrier as here shown is 30 desirable in this: The weight of the bundle-carrier and its load tends to balance the weight of that portion of the machine that is on the inner side of the master-wheel. In this last-named respect it is also an advantage to have 35 the driver supported in the position shown. The driver in this position—namely, in the immediate vicinity of the outer side of the bundle-carrier—also can better observe and control the operation of the bundle-carrier. 40 The seat L and seat-support l , as well as the person itself of the driver, are also useful in arresting the progress of the bundles in the event they are thrown too violently or blown by the wind too far across the top of the bundle-carrier, for occasionally, in a high wind 45 or when the machine is inclined toward the bundle-carrier side, the side b' of the bundle-carrier may be insufficient to always arrest the entering bundles.

50 So far as the balancing of the machine by placing the binder mechanism and the bundle-carrier upon opposite sides of the master-wheel is concerned, the bundle-carrier can be made to discharge its load automatically, for by locating the binder mechanism upon the inner side of the master or drive wheel, substantially as shown, ample space is provided on the outer side of the drive-wheel for carrying a large number of bundles, and even enough to form 55 a shock, in which case the carrier can be mechanically operated.

When the binder mechanism is located on the outer side of the drive-wheel casing, the bundle-discharger has only to shift the bundles 60 from the region of the binder into the carrier; but when the binder mechanism is located upon the inner side of the drive-wheel

casing, as here shown, the bundle-discharger must also be adapted for lifting the bundles over the casing. Such discharger may be variously constructed. As here shown it is substantially as follows: A fork, h , consisting of the head h' and fingers $h^2 h^2$, is adapted to be moved upward and downward on the way I, starting from the immediate vicinity of the 70 binder C and moving upward to the upper end of the way I and then returning to its starting-point. The fork-head h' is at h^3 pivoted to a trip, h^4 , which in turn is slotted at h^5 to engage with a stud, h^6 , that is attached to 75 the chain h^7 . This chain passes around the binder C and moving upward to the upper end of the way I and then returning to its starting-point. The fork-head h' is at h^3 pivoted to a trip, h^4 , which in turn is slotted at h^5 to engage with a stud, h^6 , that is attached to 80 the chain h^7 . This chain passes around the sprocket-wheels $h^8 h^8$. Power may be communicated to the wheels $h^8 h^8$, causing the chain to move as indicated by the arrow in Fig. 3. This, through the stud h^6 and trip 85 h^4 , causes the fork to be drawn downward to the binder C. In the downward movement of the fork the head h' is turned to throw the fingers $h^2 h^2$ flatwise into the plane of the way I; but as the stud h^6 is carried around the 90 lower wheel h^8 the stud moves to the opposite end of the slot h^5 . This movement of the stud causes the trip to be tilted on its pivot h^3 . The trip is provided with a projection, h^9 , Figs. 3, 4, 95 and 5, which as the trip is tilted comes from beneath against a projection, h^{10} , on the fork-head, causing the fork to assume an upright position at right angles to the way I, as shown in Fig. 5. In this position the fork encounters the bundle delivered from the binder, and the 100 bundle is then, by means of the upward movement of the fork, transferred to the upper end of the way I. The fork-head is provided with a pinion, h^{11} , Figs. 6 and 7, and as the fork approaches its upward limit the pinion engages in a short rack, h^{12} , that is upon the 105 way I. This causes the fork to turn from the upright position of Figs. 5 and 6 into the position of Fig. 7 and to discharge the bundle into the bundle-carrier B. The fork is then, 110 by the chain h^7 , drawn downward upon the way I. As the stud h^6 is carried around the upper wheel h^8 it moves back again to the (as shown in Fig. 3) right-hand end of the slot h^5 , causing the trip to be tilted back into 115 its original position and so as to withdraw the projection h^9 from the projection h^{10} . The fork then turns back into its original position of Figs. 3 and 4, the backward movement being initiated by the pinion h^{11} rolling backward in the rack h^{12} . The operation is then 120 repeated.

The separator G is provided with fingers $g g$ for separating and elevating the cut grain. The fingers are adapted to feather as they 125 reach the binder C—that is, the cut grain as it comes directly or indirectly from the rake is taken by the separator-fingers and by them presented in gavels to the binder, and to that end the separator is in immediate proximity to the binder. This association is maintained in all positions of the binder. The action of the separator-fingers is indicated by the drawings, and the arrow at that point indicates the 130

direction of the movement of the separator-shaft. Any equivalent gavel forming and presenting mechanism answers my purpose.

I claim—

5 The combination, in a self-binding harvester, of the following elements: a rake for transferring the cut grain to the vicinity of the binder, a separator for taking the cut grain thus delivered and presenting it in gavels to the binder, 10 a bundle-ejector, and a bundle-carrier, said bundle-ejector being independent of the separator and binder, and its path lying outside the bundle-carrier, and being adapted to de-

liver the bound bundles separately and independently of each other from the binder into 15 the bundle-carrier, and said bundle-carrier being located at a level beneath that at which the bundle leaves the ejector, said bundle-carrier being provided with means whereby it may be operated to discharge its contents at 20 the will of the driver.

WILLIAM H. PAYNE.
